WINDOW VENTILATOR

Filed Oct. 9, 1928

Watson E. Coleman
Attorney

UNITED STATES PATENT OFFICE

EARL R. HERREN, OF LORAIN, OHIO

WINDOW VENTILATOR

Application filed October 9, 1928. Serial No. 311,344.

This invention relates to a ventilator and has for its primary object to provide a ventilator which may be removably positioned in a window to permit admittance of air without admitting insects or dirt or dust.

Another object of the invention is to provide a removable window ventilator which may be adjusted to different types and sizes of windows.

10 A still further object of the invention is to provide an adjustable window ventilator having a screen or curtain which may be used to regulate the admittance of air through the ventilator.

15 The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claim.

In the drawing:—

Figure 1 is a top plan view of the ventilator embodying the present invention;

30 Figure 2 is a front elevational view of one end of the ventilator;

Figure 3 is a transverse section taken on the line 3—3 of Figure 1;

Figure 4 is a section taken on the line 4—4 of Figure 2.

Referring to the drawing in detail, the numeral 1 indicates generally the ventilator embodying the present invention, the same being formed in two sections, each of which is indicated by the numeral 2. As shown, each of the sections is relatively long and comprises a relatively flat casing 3 open along one longitudinal edge as indicated at 4 and having its opposite edge portion turned to provide the 40 upwardly directed section 5, the longitudinal edge of which is open throughout as indicated at 6.

The inner edges of the casing 3 are rolled as indicated at 7 and the inner end of each is 50 open, one of the open ends of one casing tele-

scoping into the adjacent open end of the other casing, thus making the entire ventilator structure longitudinally adjustable.

A screen of relatively fine mesh is secured over the inner open edge 4 of the casing as indicated at 8 which prevents the entrance of insects or dust and leaves. At the open outer edge, each of the upturned portions 5 is provided at its outer end with a reel 9 upon which is wound a cloth curtain or screen 10. 55 The side walls of the casing adjacent the open outer edge 6 are provided with a longitudinally extending series of apertures 11 into which may be engaged suitable fastening devices carried at the opposite edges of the curtains adjacent the free ends of the same so that these curtains may be adjustably secured in partly drawn out condition to regulate the entrance of air into the ventilator structure. 60

The inner wall of the upturned portion 70 5 of each of the sections of the ventilator structure is provided with a series of apertures 12 through certain aligned ones of which a suitable securing member such as a bolt or the like (not shown) may be passed to maintain the sections in the proper relation after the same have been adjusted to fit the ventilator to a particular window. 75

As shown when the present ventilator device is in position, the horizontal portions of 80 the casings 3 rest upon the window sill and the overlying window sash is lowered to rest upon the top of the casing, the upturned portions 5 of the sections being positioned exteriorly of the window. 85

From the foregoing, it will be readily seen that the ventilator herein described may be economically constructed from pressed metal and the construction of the same is such that it may be readily employed in any window 90 opening and will effectively prevent the entrance of undesirable matter while at the same time allowing free entrance of air into the room.

Having thus described my invention what 95 I claim is:—

A window ventilator comprising an elongated hollow body formed of a pair of telescopically associated portions, said body being of substantially L-shaped cross sectional 100

design and open along each longitudinal edge, a screen body closing one longitudinal edge, reels arranged in the ends of the body adjacent the other longitudinal edge, a flexible strip wound upon each of said reels and adapted to be drawn therefrom longitudinally of the adjacent open edge to close the same, and a pin member extending transversely of the free end of each flexible strip adapted to have its ends positioned in apertures formed longitudinally of the opposed walls of the body for maintaining the flexible strip in adjusted position.

In testimony whereof I hereunto affix my signature.

EARL R. HERREN.
